ATTACHMENT FOR DRILLING MACHINES

Georg R. Wolfe, Offenbach (Main), Germany, assignor to M. S. O. Maschinen- und Schleifmittelwerke Aktiengesellschaft, Offenbach (Main), Germany, a German company

Application September 5, 1957, Serial No. 682,232

Claims priority, application Germany September 7, 1956

9 Claims. (Cl. 51—245)

This invention relates to internal grinding attachments of the type adapted to be fitted to the inner spindle of a drill in order that the same may be used for grinding out bores. Since such attachments restrict the working height of the drill spindle driving them, these attachments must have as small an overall length as possible, while allowing the spindle bearing the grinding tool to be considerably offset from the driving drill spindle.

According to the invention there is provided a grinding attachment adapted for connection to the spindle of a drill, wherein a bushing adapted to carry an internal grinding spindle is mounted so as to be pivotable about a first pivot pin carried eccentrically by a bearing ring. The bearing ring is arranged in a housing of the attachment so as to be concentric with the drill spindle, when the attachment is connected thereto, and is arranged to be driven by the drill spindle through a countershaft and transmission means. A toothed rim is rotatably mounted on the bearing ring and is adjustable relative thereto, the toothed rim being coupled to the bushing by a second pivot pin, and being arranged to be driven by the countershaft and transmission means at the same speed as the bearing ring.

The bearing ring may be associated with a gear wheel on the countershaft through another toothed rim which is rigidly secured to the bearing ring, while the toothed rim which is rotatable on the bearing ring may engage with a gear wheel which is freely rotatable on the countershaft. The gear wheel is drivable through the agency of planetary bevel gears mounted thereon and forming part of the transmission means. The bevel gears may be mounted on radial pins of a driving bushing secured to the countershaft and may engage with a bevel gear which can be displaced by a worm drive. Advantageously, the second pivot pin is engaged by a forked arm of the bushing, the forked arm and the first pivot pin lying opposite one another on a diameter of the bushing.

The attachment has a small overall length and permits the grinding spindle to be pivoted over a wide radius, so that the scale of adjustment can be substantially linear.

For a better understanding of the invention and to show how the same may be carried into effect, reference will now be made to the accompanying drawings, wherein:

Fig. 1 is an axial section through an attachment adapted to be fitted to the inner spindle of a drill, and

Fig. 2 is a sectional view taken along the line II—II of Fig. 1.

Referring now to the drawings, the attachment comprises a casing 2 which is releasably flanged onto the drill head 1 of a drill, and a drive shaft 3 on which is mounted a pinion 4 and which is coupled to a drill spindle, the drive shaft 3 extending into the casing 2 centrally thereof. The pinion 4 meshes with an intermediate wheel 5, which in turn, meshes with a gear wheel 6 mounted on a countershaft 7 disposed parallel to the shaft 3 in a lateral extension 8 of the casing 2.

A bushing 9 is secured to the shaft 7, the bushing 9

2

having two diametrically opposed radially extending pins 10 and 11, planetary bevel gears 12 and 13 being rotatably mounted one on each such pin. The two bevel gears 12 and 13 mesh, on opposite sides of the bushing 9, with bevel gears 14 and 15, the bevel gears 14 and 15 being freely rotatable on the shaft 7. The bevel gear 14 is coupled to a worm wheel 16 the position of which can be adjusted by a handle (not shown) connected to a worm 17. The setting of the worm wheel 16 can be read on a scale 30 associated in known manner with the handle. The bevel gear 15 is integral with a gear wheel 18, and a gear wheel 19 is secured to the shaft 7.

An internal grinding spindle 20, 21 is disposed in a two-part bushing 22 which is mounted so as to be pivotable about a pivot pin 23 carried eccentrically by a bearing ring 24. The bearing ring is rotatable in the casing 2 and carries a toothed rim 25 which meshes with the gear wheel 19. An annular toothed rim 26, concentric with the bearing ring 24 and meshing with the gear wheel 18 is rotatably secured to the bearing ring 24 between lugs 29 formed in the bushing 22, the lugs 29 extending into radial slots formed in the bearing ring 24, and thereby serving to guide the bushing 22. The side of the bushing 22 remote from the pin 23 is provided with a forked arm 27 by means of which the bushing 22 is guided on a pivot pin 28 passing through the toothed rim 26.

The arrangement of the gear wheels is such that, in the operation of the attachment when the worm wheel 16 is stationary, and the shaft 7 is driven by the shaft 3 through the gear train 4, 5 and 6, the gear wheel 18 rotates in the same direction as the shaft 7 and at twice the speed thereof, while the gear wheel 19 is driven at the speed of the shaft 7. Also, the velocity ratio between the gear wheel 18 and the toothed rim 26 is twice as great as the velocity ratio between the gear wheel 19 and the toothed rim 25, and since the gear wheel 18 is driven by the shaft 7 at twice the speed of the gear wheel 19, the two toothed rims 25 and 26 rotate at the same speed.

With the drive shaft 3 stationary, the eccentric setting of the bushing 22 bearing the internal grinding spindle 20, 21 can be adjusted by the worm 17, since by turning the worm 17 the gear train 16, 14, 12, 13, 15 and 18 is actuated to rotate the toothed rim 26, thereby pivoting the bushing 22 about the pin 23 of the bearing ring 24. This pivoting action controls the axial relationship of shaft 3 and spindle 21. However, in the operation of the attachment with the worm wheel 16 stationary and the bushing 9 being rotated by the shaft 7, the rotation of the bushing 9 causes the two bevel gears 12 and 13 to roll on the bevel gear 14 which remains stationary and to drive the bevel gear 15 and the integral gearwheel 18. An additional advance or return motion can now be imparted to the gearwheel 18 and therefore to the toothed rim 26 by adjusting the worm 17 and therefore the bevel gear 14. Such additional motion pivots the bushing 22 around the pin 23, so that the internal grinding spindle is moved out of the position in which it is central relatively to the drill spindle. Since the pivoting radius of the bushing 22 is relatively large, the scale division on the scale 30 associated with the worm 17 can be substantially linear. The pivoting of bushing 22 causes spindle 21 to be axially offset relative to shaft 3 so that, for example, an internal bore-grinding operation can be controlled. Thus, for example, the diameter of a bore can be increased.

I claim:

1. A grinding attachment adapted for connection to the spindle of a drill, comprising a casing for connection to the drill head of a drill, a bearing ring disposed in said casing, a first pivot pin mounted eccentrically in said

bearing ring, a bushing mounted in said bearing ring so as to be pivotable about said first pivot pin, and adapted to carry an internal grinding spindle, a toothed rim rotatably mounted on the bearing ring, a second pivot pin connecting said toothed rim to said bushing, a countershaft and transmission means operative on said countershaft for connecting the drill spindle to the bearing ring and the toothed rim to drive the bearing ring and the toothed rim at the same speed.

2. A grinding attachment as claimed in claim 1, comprising a gearwheel on the countershaft and a toothed rim on the bearing ring and which meshes with said gearwheel, the gearwheel being a part of said transmission means.

3. A grinding attachment as claimed in claim 1, comprising a gearwheel freely rotatable on the countershaft and planetary bevel gears on the countershaft for driving the gearwheel, the bevel gears together with said gearwheel forming a part of said transmission means, the toothed rim meshing with said gearwheel.

4. A grinding attachment adapted for connecting an internal grinding spindle to the spindle of a drill having a drill head, comprising a casing for connection to the drill head, a bearing ring disposed in said casing, a first pivot pin mounted eccentrically in said bearing ring, a bushing mounted centrally in said bearing ring and pivotable about said first pivot pin and adapted to carry the internal grinding spindle, a toothed rim rotatably mounted on the bearing ring, a second pivot pin connecting said toothed rim to said bushing, a countershaft, transmission means for connecting the drill spindle to the countershaft and connecting the countershaft to the bearing ring and the toothed rim to drive the bearing ring and the toothed rim at the same speed, and manually operable means for pivoting said bushing about said first pivot pin.

5. A grinding attachment as claimed in claim 4, wherein in said manually operable means comprises a manually adjustable worm, a worm wheel operatively associated with said transmission means and meshing with the worm, the worm being operative through said worm wheel and transmission means to cause pivoting of said bushing about said first pivot pin.

6. A grinding attachment adapted for connecting an internal grinding spindle to the spindle of a drill having a drill head, comprising a casing for connection to the

- drill head, a bearing ring disposed in said casing, a first pivot pin mounted eccentrically in said bearing ring, a bushing mounted in said bearing ring and pivotable about said first pivot pin and adapted to carry the internal grinding spindle, a first toothed rim rotatably mounted on the bearing ring, a second pivot pin connecting said first toothed rim to said bushing, a second toothed rim fixedly attached to said bearing ring, a countershaft, a gear train for connecting the drill spindle to the countershaft, a driving bushing secured to said countershaft, diametrically opposed radial pins on said driving bushing, first and second planetary bevel gears mounted one on each of said radial pins, third and fourth bevel gears freely rotatable about said countershaft and meshing with said first and second bevel gears, a pinion integral with said fourth bevel gear and meshing with said first toothed rim, and a gearwheel fixedly mounted on said countershaft and meshing with said second toothed rim.
7. A grinding attachment as claimed in claim 6, wherein in the first said bushing includes a forked arm which engages said second pivot pin, said first pivot pin and said forked arm lying opposite one another on a diameter of the first said bushing.
8. A grinding attachment as claimed in claim 6, wherein in the first said bushing includes radially extending lugs and the bearing ring has radial slots in which the bushing is guided by said radially extending lugs, the first toothed rim being freely rotatable between said lugs.
9. A grinding attachment as claimed in claim 6, and further comprising a worm wheel fixedly mounted on said third bevel gear, and a manually adjustable worm meshing with said worm wheel, whereby adjustment of said worm is transmitted through said gears to said first toothed rim and thus, through the agency of said second pivot pin, to the first said bushing causing pivoting thereof about said first pivot pin.
